TRAY ATTACHMENT FOR A CHAIR OR THE LIKE

Joseph L. Hartman, Toledo, Ohio

Application June 7, 1954, Serial No. 30,841

Term of patent 7 years

(Cl. D15—8)

FIG. 1.

FIG. 2.

FIG. 3.

Figure 1 is a perspective view illustrating the front and one side of a tray attachment for a chair embodying my new design, the fragmentary chair shown in broken lines being for illustrative purposes only;

I claim:

The ornamental design for a tray attachment for a chair or the like, as shown and described.
